UNITED STATES PATENT OFFICE

99,260

DESIGN FOR A SHOE

Albert F. Bancroft, Newton, Mass.

Application January 30, 1936, Serial No. 60,899

Term of patent 7 years

To all whom it may concern:

Be it known that I, Albert F. Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a plan view of a shoe showing my new design,

Fig. 2 is a view in side elevation showing the inside quarter, which is a contrasting color, merging into a broad band of substantially the same width which crosses the instep of the shoe and is secured at the opposite side by two buttons, the heel being shown conventionally in dotted lines, and

Fig. 3 is a view in side elevation of the shoe as seen from the side opposite that shown in Fig. 2.

The dominant feature of my design resides in a combination of elements including the inside quarter of the shoe which is carried across the instep in the form of an integral cross strap located relatively high up on the instep and presenting a square ended effect and being secured to the outer quarter by two spaced buttons, the outer quarter being extended upwardly into a peak located in the outer side of the shoe and extending at its point above the cross strap.

I claim:

The ornamental design for a shoe substantially as shown and described.

In witness whereof, I have affixed my signature hereto.

ALBERT F. BANCROFT.
